UNITED STATES PATENT OFFICE.

OSWALD WOLLENWEBER, OF MARION, OHIO.

DESIGN FOR A SPLIT-PULLEY SPOKE-ARM.

SPECIFICATION forming part of Design No. 33,299, dated October 2, 1900.

Application filed July 21, 1900. Serial No. 24,448. Term of patent 14 years.

To all whom it may concern:

Be it known that I, OSWALD WOLLENWEBER, a citizen of the United States, residing at Marion, in the county of Marion and State of Ohio, have invented and produced a new and original Design for Split-Pulley Spoke-Arms; and I do declare the following to be a full, clear, and exact description of the invention, such as will enable others skilled in the art to which it appertains to make and use the same, reference being had to the accompanying drawing, and to the letters of reference marked thereon, which form a part of this specification.

15 My design relates to a spoke-arm for a split-wood pulley, and is illustrated in the accompanying perspective view.

As shown in the drawing, the leading or material feature of my design consists of a spoke-arm, which is in the main an elongated wooden bar rectangular in transverse section and corresponding in length with the diam-

eter of its pulley. Each end of the bar is chamfered or beveled on two opposite sides toward the end, as at *a*. Across each of the 25 extremities of the spoke-arm is formed the segment of a solid cylinder *b*, the axes of which two cylinders lie parallel to each other. Midway of the length of the spoke-arm a rectangular notch or gain *c* is cut from one of the 30 sides of the spoke-arm, as shown.

Having described my invention, what I claim as new, and desire to secure by Letters Patent, is—

The design for a split-pulley spoke-arm as 35 herein shown and described.

In testimony whereof I affix my signature in presence of witnesses.

OSWALD WOLLENWEBER.
